Primary Examiner — Catherine A Tuttle*(74) Attorney, Agent, or Firm* — Law Offices of Steven W. Weinrieb(57) **CLAIM**

The ornamental design for a toy, as shown and described.

DESCRIPTION

FIG. 1 is a front, right side, top perspective view of the toy showing my new design;

FIG. 2 is a rear, left side, top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict features of the toy that form no part of the claimed design, with the perimeters of the various broken line features serving to define the bounds of the claim adjacent to the shaded areas.
